[57] ABSTRACT

Certain bridged 1,5-diazacyclodecanes, e.g., 9-phenyl-1,5-diazabicyclo[4.3.1]decanes are useful as anti-ulcer agents.

6 Claims, No Drawings

DIABICYCLOCODECANES AS ANTI-ULCER AGENTS

This invention relates to the pharmaceutical activity of diazabicyclodecane derivatives. More particularly, this invention concerns the use of 1,5-diazabicyclo[4.3.1]decanes in the treatment of ulcers in mammals. The invention also relates to pharmaceutical compositions containing the above compounds as an active ingredient thereof.

The active agents with which this invention is concerned may be represented by the following structural formula:

where

R is hydrogen, fluoro, chloro or lower alkoxy, i.e., alkoxy having 1 to 4 carbon atoms, e.g., methoxy, ethoxy, isopropoxy and the like, or pharmaceutically acceptable salts thereof.

This invention contemplates only the novel use of the compounds of formula (I) in the treatment of ulcers and pre-ulcer conditions such as severe irritation of the gastrointestinal tract.

Many of the compounds of formula (I) above are known and may be prepared according to methods disclosed in the literature, for example, in U.S. Pat. No. 3,517,004. The compounds not specifically disclosed in the literature may be prepared by analogous methods using known starting materials.

The pharmaceutically acceptable salts include the non-toxic pharmaceutically acceptable acid addition salts. Such salts possess the same order of activity as the free base, are readily prepared in conventional manner by reacting the base with the appropriate acid and are included within the scope of the invention. Representative of the acid addition salts are the mineral acid salts such as the hydrochloride, hydrobromide, sulphate, phosphate and the like, and the organic acid salts, such as the succinate, benzoate, acetate, p-toluenesulfonate, benzenesulfonate and the like.

The use of the compounds of formula (I) as anti-ulcer agents is suggested by their autonomic profile as indicated by blood pressure changes in the anesthetized dog given 1 to 10 milligrams per kilogram of test compounds intravenously as measured with the aid of a mercury manometer or transducer via a catheter inserted in either the carotid or femoral artery of the animal and recorded either on a kymograph or an appropriate electronic recorder. The surgical method of preparing the animal is a modification of that described by Markowitz (Exper. Surgery, Williams and Wilkins, 2nd Ed., 1949). The inhibition of the depressor response (fall in blood pressure) to vagal stimulation using a Grass stimulator shows a suppression of the release of acetylcholine at the parasympathetic postganglionic

neuroeffector sites and indicates the compounds of formula (I) are useful in the treatment of ulcers.

The anti-ulcer activity of the compounds of formula (I) is indicated by the prevention of stress induced ulcers produced by cold confinement at 4°C in rats given one milligram per kilogram per hour of the test compound using a modification of the technique of Brodie, D. A., et al. (Gastroenterology 38; 353, 1960) and by the inhibition of gastrointestinal motility produced by 10 vagal stimulation using a Grass stimulator in the anesthetized dog given 1 to 10 milligrams per kilogram of the test compound according to the method of Craver, B. M., et al (J. Pharmacol and Exp. Ther. 93. 168, 1948).

15 For such usage, the compounds may be administered orally or parenterally as such or admixed with conventional pharmaceutical carriers. They may be administered in such forms as tablets, dispersible powders, granules, capsules, syrups and elixirs and parenterally as solutions, suspensions, dispersions, emulsions and the like, e.g., a sterile injectable aqueous suspension. The compositions may contain one or more conventional adjuvants, such as sweetening agents, flavoring agents, coloring agents and preserving agents, in order 20 to provide an elegant and palatable preparation. Tablets may contain the active ingredient in admixture with conventional pharmaceutically acceptable excipients, e.g., inert diluents, such as calcium carbonate, sodium carbonate, lactose and talc, granulating and disintegrating agents, e.g., starch and alginic acid, binding agents, e.g., starch, gelatin and acacia, and lubricating agents, e.g., magnesium stearate, stearic acid and talc. The tablets may be uncoated or coated by known techniques 25 to delay disintegration and absorption in the gastrointestinal tract and thereby provide a sustained action over a longer period. Similarly, oral liquids, e.g., suspensions may contain the active ingredient in admixture with any of the conventional excipients utilized 30 for the preparation of such compositions, e.g., suspending agents (methylcellulose tragacanth and sodium alginate) wetting agents (lecithin, polyoxyethylene stearate and polyoxyethylene sorbitan mono-oleate) and preservatives (ethyl-o-hydroxybenzoate). Capsules 35 may contain the active ingredient alone or admixed with an inert solid diluent, e.g., calcium carbonate, calcium phosphate and kaolin. The injectable compositions are formulated as known in the art. These pharmaceutical preparations may contain up to about 90 percent of the active ingredient in combination with the carrier or adjuvant.

The anti-ulcer effective dosage of the compounds of formula (I) employed in the treatment of ulcers and pre-ulcer conditions may vary depending on the particular compound employed and the severity of the condition being treated. However, in general, satisfactory results are obtained when the compounds of formula (I) are administered at a daily dosage of from about 1 milligrams to about 100 milligrams per kilogram of animal body weight, preferably given in divided doses two to four times a day, or in sustained release form. For most large mammals, the total daily dosage is from about 60 milligrams to about 1500 milligrams. Dosage forms suitable for internal use comprise from about 15 to 60 about 750 milligrams of the active compound in intimate admixture with a solid or liquid pharmaceutically acceptable carrier or diluent.

The preferred pharmaceutical compositions from the standpoint of preparation and ease of administration are solid compositions, particularly hardfilled capsules and tablets containing from about 100 to 250 milligrams of the active ingredient.

EXAMPLES 1 and 2

Tablets and Capsules Suitable For Oral Administration

Tablets and capsules containing the ingredients indicated below may be prepared by conventional techniques and are useful in treating ulcers at a dose of one tablet or capsule 2 to 4 times a day.

Ingredients	Weight (mg)	
	tablet	capsule
9-phenyl-1,5-diazabicyclo[4.3.1]decane hydrochloride	100	100
tragacanth	10	—
lactose	247.5	200
corn starch	25	—
talcum	15	—
magnesium stearate	2.5	—
Total	400 mg.	300 mg.

In a similar manner, tablets and capsules may be prepared using 9-(p-chlorophenyl)-1,5-diazabicyclo[4.3.1]decane or 9-(p-methoxyphenyl)-1,5-diazabicyclo[4.3.1]decane as the active ingredient in place of the 9-phenyl-1,5-diazabicyclo[4.3.1]decane above.

EXAMPLES 3 and 4

Sterile Suspension for Injection and Oral Liquid Suspension

The following pharmaceutical compositions are formulated with the indicated amount of active agent using conventional techniques. The injectable suspension and the oral liquid suspension represent formulations useful as unit doses and may be administered in the treatment of ulcers. The injectable suspension is suitable for administration once or twice a day whereas the oral liquid suspension is suitably administered 2 to 4 times per day for this purpose.

Ingredients	Weight (mg)	
	injectable suspension	liquid suspension
9-phenyl-1,5-diazabicyclo[4.3.1]decane	200	100
sodium carboxy methyl cellulose U.S.P.	1.25	12.5
methyl cellulose	0.4	—
polyvinylpyrrolidone	5	—
lecithin	3	—
benzyl alcohol	0.01	—
magnesium aluminum silicate	—	47.5
flavor	—	q.s.
color	—	q.s.
methyl paraben, U.S.P.	—	4.5
propyl paraben, U.S.P.	—	1.0
polysorbate 80 (e.g. Tween 80), USP	—	5
sorbitol solution, 70% USP	—	2,500
buffer agent to adjust pH for desired stability	q.s.	q.s.
water	for injection q.s. to 1 ml.	q.s. to 5 ml.

In a similar manner, injectable suspensions and liquid suspensions may be prepared using 9-(p-chlorophenyl)-1,5-diazabicyclo[4.3.1]decane or 9-(p-methoxyphenyl)-1,5-diazabicyclo[4.3.1]decane as the active ingredient in place of the 9-phenyl-1,5-diazabicyclo[4.3.1]decane above.

EXAMPLE 5

Sterile Solution for Injection

The following ingredients are dissolved in water for injection and the resulting solution is filtered through an appropriate medium to form a clear solution which is then sterilized. The sterile injectable solution is suitable for administration once or twice a day in the treatment of ulcers or pre-ulcer conditions.

20	Ingredient	Weight (mg)
9-phenyl-1,5-diazacyclo[4.3.1]decane hydrochloride	100	—
Sodium alginate	0.5	—
Buffer system	as desired	—
Lecithin	0.5	—
Sodium chloride	as desired	—
Water for injection	q.s. to 1 milliliter	—

Similar injectable solutions for injection may be prepared using 9-(p-chlorophenyl)-1,5-diazacyclo[4.3.1]decane hydrochloride or 9-(p-chlorophenyl)-1,5-diazabicyclo[4.3.1]decane hydrochloride in place of the 9-phenyl-1,5-diazabicyclo[4.3.1]decane hydrochloride above.

EXAMPLE 6

Syrups and Elixirs for Oral Administration

The following formulations for syrups or elixirs containing an effective amount of active compound may be formulated using conventional methods and are suitable for administration 2 to 4 times a day in the treatment of ulcers and pre-ulcer conditions.

Ingredient	Percent by Weight	
	syrup	elixir
9-phenyl-1,5-diazabicyclo[4.3.1]decane hydrochloride	.5-3.5	.5-3.5
Buffering system	quantity sufficient to adjust pH	—
Sodium benzoate	.1-.5	.1-.5
Flavoring agent	.01-.2	.01-.2
Water	20-40	5-20

Ingredient	Percent by Weight	
	syrup	elixir
Simple syrup U.S.P.	30-70	0
Sorbitol solution (70%)	10-30	20-60
Certified dye	.5-2	.5-2
Alcohol	0	2.5-20
Methyl paraben	0	.05-.1
Propyl paraben	0	.05-.1
Sodium cyclamate	0	.1-.4
Sodium saccharin	0	.01-.04

Analogous compositions to those above may be prepared using the hydrochloride salt of 9-(p-chlorophenyl)-1,5-diazabicyclo[4.3.1]decane or 9-(p-methoxyphenyl)-1,5-diazabicyclo[4.3.1]decane in place of the 9-phenyl-1,5-diazabicyclo[4.3.1]decane hydrochloride.

What is claimed is:

1. A method of treating gastrointestinal ulcers in a mammal, which comprises administering thereto an anti-ulcer effective amount of a compound of the formula:

where R is hydrogen, fluoro, chloro or lower alkoxy or a pharmaceutically acceptable acid addition salt thereof.

2. The method of claim 1 wherein the compound is administered at a daily dosage of from about 60 milligrams to about 1500 milligrams.

3. The method of claim 1 wherein the compound is administered in a unit dosage form comprising from about 15 milligrams to about 750 milligrams of said compound per unit dosage.

4. The method of claim 1 in which the compound is 9-phenyl-1,5-diazabicyclo[4.3.1]decane.

5. The method of claim 1 in which the compound is 9-(p-chlorophenyl)-1,5-diazabicyclo[4.3.1]decane.

6. The method of claim 1 in which the compound is 9-(p-methoxyphenyl)-1,5-diazabicyclo[4.3.1]decane.
